UNITED STATES PATENT OFFICE.

ROBERT H. WARREN AND DAVID WALKER, OF NEWARK, NEW JERSEY.

DESIGN FOR A STAIR-CARPET BUTTON.

SPECIFICATION forming part of Design No. 23,347, dated June 12, 1894.

Application filed May 15, 1894. Serial No. 511,367. Term of patent 7 years.

To all whom it may concern:

Be it known that we, ROBERT H. WARREN and DAVID WALKER, citizens of the United States, residing at Newark, in the county of Essex and State of New Jersey, have invented and produced a new and original Design for Stair-Carpet Buttons; and we do hereby declare the following to be a full, clear, and exact description of the invention, such as will

- enable others skilled in the art to which it appertains to make and use the same, reference being had to the accompanying drawings, and to letters of reference marked thereon, which form a part of this specification.
- 5 Figure 1 is a plan showing our design, and Fig. 2 is a central section of the same, these two views being deemed necessary to fully illustrate our design.

The leading feature of our design consists in a stair button, on the face of which is displayed two annular and concentric series of radiating petal-shaped ornaments.

a, indicates a round stair button, around the central perforation of which are displayed two annular series of petal-shaped ornaments, *b*, and *c*, the inner series being raised considerably above the outer series, as will be understood upon reference to Fig. 2. Between the petals of the outer series, are displayed radial lines *d*, terminating in dots, *e*, closely adjacent to the periphery of the button.

What we claim as new is—

The design for a stair button herein shown and described.

In testimony that we claim the foregoing we have hereunto set our hands this 10th day of May, 1894.

ROBERT H. WARREN.
DAVID WALKER.
